UNITED STATES PATENT OFFICE.

HIRAM C. CLARKE, OF WEST WINFIELD, NEW YORK.

DESIGN FOR A PUZZLE-BOX.

SPECIFICATION forming part of Design No. 28,614, dated May 10, 1898.

Application filed January 6, 1898. Serial No. 665,864. Term of patent 3½ years.

To all whom it may concern:

Be it known that I, HIRAM C. CLARKE, of West Winfield, in the county of Herkimer and State of New York, have invented and produced a new and original Design for a Puzzle-Box, of which the following is a specification.

The design relates to puzzle-boxes in which a labyrinth is provided, through the mazes of which marbles may be caused to travel; and the design consists in the novel configuration of the base and walls forming the labyrinth, as shown in the accompanying drawings, in which—

15 Figure 1 represents a plan view of a puzzle-box embodying my design, and Fig. 2 is a cross-section on the line 2 2 of Fig. 1.

Thus the leading feature of the design consists in a box comprising the base *a* and walls 20 or partitions *b*, the base having rounding marginal lines *a'* *a'*, the marginal lines at opposite sides of the base having an inward trend, as at *a*³, and joining the marginal lines of smaller laterally-projecting members *a*² *a*², the

defining-lines of which are also rounding, as 25 shown. The walls start in scrolls at the respective lateral extensions *a*² of the base and form passages *c* *c*', each of which leads from an inclosure *d* in the said extensions *a*², skirting the latter, thence to one end edge *a*', after 30 skirting which the passage deflects to the opposite end *a*', where it winds in a more or less true helical form to an inclosure *e*, adjacent to which inclosures the walls *b* deflect to form angles *b*'. Further, breaks *f* appear in the 35 walls *b* at points about equidistant from the inclosures *d* and *e* and between said inclosures; but these breaks and their positions are of minor importance in the design.

Having described my invention, what I 40 claim as new, and desire to secure by Letters Patent, is—

The design for a puzzle-box, as herein shown and described.

HIRAM C. CLARKE.
